Fig. 3.

UNITED STATES PATENT OFFICE.

BENJAMIN E. MEACHAM, OF LORAIN, OHIO, ASSIGNOR TO AMERICAN STOVE COMPANY, OF ST. LOUIS, MISSOURI, A CORPORATION OF NEW JERSEY.

AUTOMATIC WATER-HEATER.

1,103,800.

Specification of Letters Patent. Patented July 14, 1914.

Application filed April 4, 1912. Serial No. 688,501.

To all whom it may concern:

Be it known that I, BENJAMIN E. MEACHAM, a citizen of the United States, residing at Lorain, in the county of Lorain, in the State of Ohio, have invented certain new and useful Improvements in Automatic Water-Heaters, of which the following is a specification, reference being had therein to the accompanying drawing.

10 My invention relates to improvements in automatic water heaters.

The object of my invention is to provide a heater of this character in which the flow of water through the heater is retarded until 15 it has reached a certain temperature, whereby there is a saving in fuel and also preventing a large quantity of partially heated water from passing from the heater and at the same time providing a heater in which 20 the water is heated much more quickly.

Another object of my invention is to provide a heater of this character in which the water discharge pipe forms the means by 25 which the flow of water is controlled and also forming the means for controlling the gas supply to the burner.

A further object of my invention is to provide a device of this character in which there is a circulation of water through the coils 30 after the water is cut off, should the gas valve become stuck and the burner remain lighted, whereby the coils would not be as readily burned out or injured by the intense heat from the burner.

35 A still further object of my invention is to provide a simple, cheap and very effective means for accomplishing the above results having certain details of structure hereinafter fully set forth.

40 In the accompanying drawings: Figure 1 is a side elevation, of a water heater showing my attachment applied thereto. Fig. 2 is a vertical sectional view of the water heater shewing the attachment in full line and 45 locking in a direction at right angles to Fig. 1. Fig. 3 is an enlarged vertical sectional view taken on the line 2—2 Fig. 2. Fig. 4 is a vertical sectional view of the upper end of the attachment as shown in 50 Fig. 3, only taken at right angles to Fig. 3. Fig. 5 is a vertical sectional view taken on the line 5—5, Fig. 2.

In water heaters of this character heretofore used, the gas supply to the main burner is controlled by the opening and

closing of the spigot or faucet in the water discharge leading from the heater and in such cases the opening of the spigot allows a full flow of water through the heater. In such heaters before water which is heated to 60 the desired temperature passes therefrom, a large quantity of partially heated water passes from the heater which is not only a waste of water, but consumes considerably more fuel before water of the desired temperature is obtained; and at the same time taking a much longer time to get the water up to the desired temperature. 65

In my improved heater the passage of the water through the heater is retarded until 70 it has reached the desired temperature, whereby a great saving in water, fuel and time is the result.

Referring now to the drawings, 1 represents the body of my improved heater which, 75 as shown, is the double wall construction and which needs no further description. Within said body portion of the heater is the coil 2 through which the cold water passes, and is heated in the well-known manner by burners 3 at the lower end. Within the body portion adjacent the burners is a pilot-light which is at all times burning and whereby the main burners are ignited when the gas is turned on thereto, as will be hereinafter more fully described. 80

The main water supply pipe 4 leads from any water supply source and is connected to a cylinder 5, in which is located the piston 6, normally held to the left by means of a 90 spring 7, mounted upon the piston-rod 8, carried by the piston. The said piston-rod extends out through a stuffing box 9 and is adapted to operate the gas supply valve, as will be hereinafter more fully described. 95

The cylinder 5 in one side is provided with an opening 10, which communicates with a pipe 11, which leads upwardly and is connected to the upper end of the coil 2, and whereby the coil is fed with water at its 100 upper end.

The water enters the coil at the upper end and passes downward therethrough and passes from the coil at 12 into a connection 13 to which is connected a pipe 14, which leads upwardly, as clearly shown in Figs. 1 and 3, and has a screw-threaded connection with a housing 15. The housing 15 has a laterally extending pipe 16 connected thereto and which is adapted to convey the water 110

to the desired point. The connection 15 has a downwardly extending plate carried thereby, which is provided at its lower end with a lateral ear 17 secured to the cylinder 5 and 6 whereby said plate and connections 13 are supported in the position shown.

Surrounding the pipe 14 loosely, so that it is free to move vertically thereon, is a plate 18 which is provided with an upwardly 10 extending yoke 19 surrounding the housing 15, and whereby the housing and pipe 14 are free to move vertically independent of the yoke. The yoke is preferably made of two sections 20 and 20', bolted together at 15 21, whereby the yoke may be readily removed when desired. The plate 18 is secured to bolts 22 and 23, which extend downwardly and are secured to the connection 13, as shown. The connection between the pipe 18 and the bolts 22 and 23 is by means of the nuts 24 and 25 above and below the plate, whereby the plate is vertically adjusted to 20 or from the connection 13 for a purpose which will be hereinafter more fully described.

The main burner is supplied with gas by means of a pipe 26, which has its upper end connected to the gas valve casing 27. This valve casing is of a double valve form for a 30 purpose later described and is cast in one piece having the two valves 28 and 29 therein. The upper end of the valve case 27 has connected thereto a gas supply pipe 30, which communicates with the upper valve 28. 35 These two valves are connected or not in communication with each other through a passage 31, which is controlled by a turn-plug 32, as clearly shown in Fig. 3, of the drawing. The upper valve 28 is provided 40 with a spring which normally tends to hold the valve closed. The valve 29 has a stem 34 extending outwardly through a stuffing box and said valve stem is engaged by the lever 36 which is normally held in a position 45 to hold the valve 28 unseated, as shown in Fig. 3, of the drawings, and whereby the gas is allowed to flow thereby and is controlled by the turning plug 32.

The valve casing 27 is secured to the plate 17 by means of the lateral ears 17 and 18, shown in Fig. 2 of the drawings. The lower valve 29 is exactly the same as the upper valve 28 and is normally held seated by a spring 39. The valve casing 27 is provided 55 with caps 40 and 40' opposite the valves and into which extends the springs, and whereby access may be readily had to the valves. The valve 29 has a stem 34 extending outwardly through the stuffing box 33, and is in exact 60 alinement with the stem 8 of the piston 3, and whereby the movement of the piston to the right by the water pressure heretofore described, unseats the valve 29 and the valve 28 being normally unseated, the gas is al- 65 lowed to pass to the main burner and the

heater is set in full operation. The pilot light of the burner is fed by a pipe 29', which is connected to the valve casing 27, above the upper valve 28, whereby it is always supplied with gas.

Carried by the housing 15 is a rod 43, which extends downwardly and loosely passes through the connection 13 and engages a flat portion 44 of the lever 45 pivoted at 46. The lower end of the lever 45 has an enlarged portion 47 through which passes a set screw 48, which engages the lever 36 below its pivot 36'. The set-screw 48 is so adjusted that when the water in the heater is cold, the lever 36 holds the valve stem 34 to the right and the valve is held open, so that the gas can pass to the burner.

The housing 15 has a transverse division plate 49 provided with an opening 50 closed by the valve 51. The said valve is normally closed by the spring 52 and the valve is so constructed that it does not tightly fit the seat and there is always a small leakage of water therearound, so that as soon as the water is turned on, there is a slight circulation of water through the heater.

The transverse division plate 19 is arranged in the housing in a horizontal position intermediate the inlet and outlet of the said housing.

Pivotedly mounted on the lower face of the plate at 53 is a lever 54, which has its outer free end engaging the valve 51, and the spring 52 engaging the lever normally holds the valve closed. The lever intermediate its ends is provided with an upwardly extending lug or pin 55, which extends through the plate 49. Pivoted to the upper face of the plate 19 at 56 is a lever 57, which is directly above the pin 55 and engages the same.

Straddling the lever 57 is a vertically movable rod 58, which extends through the stuffing box 59 carried by the upper end of the housing. The said rod is secured into the nut 60, which is rotatably mounted in the recess 61, carried by the upper end of the yoke 19. This nut 60 is free to rotate in the recess and is provided with a peripheral groove 62 into which extends a set-screw 63, carried by the yoke, whereby the nut is free to rotate yet held against downward movement. The rotation of the nut, as will be readily seen, moves the rod 58 up or down for the adjustment of the lever 57, whereby the slight movement of the housing 15 will move the valve 51 and allow a full flow of water from the heater. The tube 14 is made of copper or brass and is very expandable, whereby the heated water in the tube will expand the tube causing it to move upwardly carrying with it the housing 15, and the rod 58 being held by the nut in the yoke will force the lever 57 which engages the pin 55 to move the lever 54 and unseat the valve, which allows a full flow of water

through the heater. A continued expansion of the tube 14 raises the rod 43, which releases the lever 45 and lever 36, and the spring 33 seats the valve 28 and gas is cut off. This is only effected when the water has reached an excessive heat and this is governed by the set-screw 48, as heretofore described. Secured to the housing 15, below the plate 49, is a pipe 64 which extends downwardly and is provided with a casing 65 at its lower end.

By the arrangement heretofore described it will be seen that the pipe leading from the lower end of the coil for conveying the heated water from the heater is employed, as the thermostatic means for controlling the flow of water from the heater, until it has reached a certain temperature and also serves as means for cutting off the supply 20 of gas from the burner, so that, should the water be heated beyond a certain temperature, the gas to the main burner will be cut off, as heretofore described.

As heretofore stated, the adjustment of 25 the nut 60 determines the amount of movement of the housing 15 necessary to unseat the valve 51 and whereby the valve can be opened when the water reaches any desired or predetermined temperature.

30 The turning plug 32 is operated by a lever 65' and when turned so that its ports are transverse of the valve casing the turning on of the water will not light the burner as the gas cannot get from the valve 28 to the valve 29.

The casing 65 carried by the lower end of the pipe 64 has a vertically disposed valve 66, which is held unseated by the spring 67, and whereby the communication between the 40 pipe 64 and the casing 65 is opened. The casing 65 is in communication with the pipes 68 and 69 leading from the coils and which is designed to allow of the circulation of the water through the coil after the water 45 is cut off should the burner for any reason not be extinguished. The valve 66 is normally held open and is closed by the water pressure in the pipe 64 against the valve and which overcomes the tension of the 50 spring 67.

The valve stem 68' of the valve 66 extends downwardly into a cylindrical portion 69 in the casing 65 and is provided with a series of vertically extending grooves 70 in its 55 outer periphery. Loosely fitting on the said stem is a piston 70' which tightly fits in the cylindrical portion 69' of the casing and is normally held in its downward position by the spring 67 above. The piston has its 60 downward movement on the valve stem limited by the enlarged portion 71 of the stem. The pipes 68 and 69 have no communication between each other through the housing except through the cylindrical portion 70. The lower end of said cylindrical portion

portion below the piston has a passage 72 leading upwardly around the cylinder and in communication with the pipe 68 leading from one of the coils.

In operation the water pressure closes the valve 66 and allows of a circulation of water through the coil. When the water is cut off and the burner, for any reason, should continue to burn, the heated water would pass through the pipe 64 into the passage 69 of the other coil and whereby there is a continued circulation of water through the coils as long as the burner is burning. This construction, as heretofore stated, prevents the coils from becoming injured by the excessive 80 heat which necessarily arises when the water is cut off and the burner remains in operation.

Secured to the upper end of the heater 1 is a bracket 26', which extends outwardly and has its end bifurcated and secured to the plate 18 by means of nuts 24, and whereby the plate 18 is rigidly supported by the body 1 of the heater.

Having thus described my invention, what 90 I claim and desire to secure by Letters Patent is:

1. The combination with a water heater, a burner, a gas supply for the burner, a water discharge for the heater, thermostatic 95 means for controlling the gas supply and water discharge, and automatic means for causing a circulation of the water in the heater after the water discharge is closed.

2. The combination with a water heater, 100 a burner, a gas supply for the burner, a water discharge for the heater, thermostatic means for controlling the gas supply, a water discharge controlled by the thermostatic means, and automatic means for causing a circulation of the water in the heater 105 after the water discharge is closed.

3. The combination with a water heater, a water supply for the heater, a water discharge pipe for the heater, a valve in said 110 pipe for checking the flow of water therethrough, and means operated by the expansion of said pipe for opening the valve therein and allowing a full flow of water therethrough, and means operated by the expansion of said pipe for allowing the gas valve to close when the water in the heater 115 has reached a predetermined temperature.

4. The combination with an automatic water heater, a water supply therefor, a water discharge pipe for said heater, a valve in said pipe and normally checking the flow of water from the heater, a stem carried by a stationary part of the heater and adapted to open the valve when the pipe moves outwardly by the expansion thereof and means operated by the continued expansion of the pipe to allow the gas valve to close when the water in the heater has reached a predetermined temperature.

- 4
5. The combination with an automatic water heater, a water supply therefor, a water discharge pipe for said heater, a receptacle, carried by the discharge pipe, a transverse partition carried by the receptacle and having an opening therein, a valve closing the opening but allowing a slight leakage therearound, a yoke carried by a stationary part of the heater and surrounding the receptacle, but the receptacle being free to move therein, a lever pivoted to the lower face of the partition and engaging the valve and normally holding it closed, and having a pin extending through the partition, a second lever pivoted to the upper face of the partition and engaging the pin, a vertically adjustable stem supported by the yoke and extending into the receptacle and straddling the second lever whereby the expansion of the discharge pipe moves the receptacle and the stem operates the levers for unseating the valve and allowing a full flow of water through the receptacle when the water has exceeded its predetermined temperature.
- 25 6. The combination with an automatic water heater, a water supply therefor, a gas supply valve for the burner of the heater, a water discharge pipe for said heater, a valve in said pipe and normally checking the flow of water from the heater, means operated by the expansion of the pipe for opening the valve and allowing a full flow of water through the heater, means operated by the continued expansion of the pipe to allow the gas valve to close and automatic means for connecting the coils to allow a circulation of water through the heater after the water discharge is closed.
7. The combination with a heater, a burner, a gas supply for the burner, a double valve casing for controlling the gas supply, a water supply and discharge pipes for the heater, a piston in the water supply and having a piston rod extending therefrom, a valve in the valve casing and normally held closed and having a stem in alignment with the piston rod, a second valve normally held open, means operated by the expansion of the discharge pipe for allowing the second valve to close, and means in the discharge pipe for checking the flow of water therethrough and controlled by the expansion of said discharge pipe.
8. The combination with a water heater, a burner, a gas supply for the burner, water supply and discharge pipes for said heater, a valve controlling the gas supply and normally held open, a stem carried by the valve and extending outwardly, a lever pivoted at the upper end and engaging the valve stem, a second lever pivoted above the first lever and having a set screw at its lower end engaging the first lever below its pivot, a rod carried by the discharge pipe and engaging the upper lever and holding the levers in the position shown, whereby the expansion of the pipe draws the rod upward and relieves the lever and allows the gas valve to close, substantially as shown and described.
- In testimony whereof I hereunto affix my signature in the presence of two witnesses.
